United States Patent Office

Des. 185,098
Patented May 5, 1959

185,098

DOOR KNOB

Helen F. Prescott, Sharon, Mass., assignor to Schlage
Lock Company, a corporation

Application November 25, 1957, Serial No. 48,624

Term of patent 14 years

(Cl. D50—3)

Fig. 1 is a perspective view of a door knob, showing my new design;

Fig. 2 is a side elevational view of the door knob of Fig. 1; and

Fig. 3 is a front end elevational view of the door knob of Fig. 1.

I claim:

The ornamental design for a door knob, as shown.
